UNITED STATES PATENT OFFICE.

EDWIN P. WANNER, OF NEW YORK, N. Y.

TABLE.

No. 875,755.

Specification of Letters Patent.

Patented Jan. 7, 1908.

Application filed February 4, 1907. Serial No. 355,582.

To all whom it may concern:

Be it known that I, EDWIN P. WANNER, a citizen of the United States, residing in New York city, State of New York, have invented 5 certain new and useful Improvements in Tables; and I do hereby declare the following to be a full, clear, and exact description of the invention, such as will enable others skilled in the art to which it appertains to 10 make and use the same, reference being had to the accompanying drawings, and to letters of reference marked thereon, which form a part of this specification.

This invention relates to tables and the 15 like articles of furniture having legs, horizontal supporting rails or bars which meet at an angle at each leg, and a supported part, such as the table top.

The invention consists in an improved 20 means for bracing tables and similar articles of furniture at the angles above indicated and it has particularly in view as an objection to be overcome the fact that, as between the side bars or rails, the legs and top, the 25 legs are the elements principally responsible for the loosening of the joints between these parts and that to overcome the loosening of the legs will not only preserve the stability of the table in so far as the legs are concerned 30 but will prevent the legs from disturbing the joint as the result of the leverage they exert thereon.

My invention will be found fully illustrated in the accompanying drawings, wherein, 35 Figure 1 is a fragmentary plan view of a table constructed in accordance with my invention, a part of the table top being broken away to more clearly illustrate the arrangement and construction of the bracing device 40 and the other parts; Fig. 2 is a vertical sectional view taken parallel with one side of the table and through one leaf of the brace; Fig. 3 is a horizontal sectional view of the leg on the line $x-x$ in Fig. 2; and, Fig. 4 is 45 a horizontal sectional view of the brace taken on the same line $x-x$.

In the drawings, a designates the table top and b two side rails or bars arranged at right angles to each other and coöperating with 50 the leg c to support the top a , which latter may be secured on the parts b and c in the manner hereinafter indicated or otherwise.

The leg c has two vertical faces d arranged at right angles to each other, and against 55 each of these faces d abuts the squared end e of the corresponding rail b . Where these

faces d would otherwise meet to form a right angle, a Y-shaped groove is formed in the leg vertically thereof and in a radius of the leg. This groove comprises the part f having its side walls g at right angles to each other and the narrow part h having its side walls i parallel to each other. It should be remarked that the side rails b are so arranged that their inside faces are flush with the faces 60 g of the part f of the Y-shaped groove in the leg above referred to.

j is an angle-iron or brace comprising the suitably formed leaves k arranged at right angles to each other and a web l joining said 70 leaves at the top of the brace. The leaves and the web may be formed with suitable holes m whereby to secure the brace to the two side rails or bars b and to the top a . The brace is furthermore provided on the outside 75 thereof and along the angle formed by its leaves k with a narrow fin or rib n extending preferably the full depth of the brace, and, on the inside thereof, with a boss o whose face p is at right angles to the rib n ; the brace is 80 penetrated by an opening q formed axially of the boss o . A lag screw r is passed through the opening q and driven into the leg c , its head taking against the boss o , or a washer s .

When the brace is placed in position, as 85 shown in the drawing, it projects into the portion f of the Y-shaped groove formed in the leg, and being secured to the two side rails and the top a by screws t passed through the holes m , this of itself operates largely to 90 prevent loosening between the parts; even though the rails b , for instance, should shrink so that, so far as they would be concerned, the leg c might be moved on the lag screw as a fulcrum, this action of the leg would be prevented by the brace entering and fitting into the portion f of the Y-shaped groove in said 95 leg. And this effect is very materially augmented by the rib n which, being forced snugly into the portion h of the Y-shaped groove in 100 the leg and being of material depth from the brace outwardly, removes any possibility whatever of play of the leg on its fulcrum.

Other advantages are secured by this construction which will be apparent to those 105 skilled in the art.

Having thus fully described my invention, what I claim as new and desire to secure by Letters Patent is:

1. In a table or the like, the combination, 110 with two parts arranged at an angle to each other and a third part interposed between the

adjoining ends of said first named parts, said third part having a recess substantially coincident with the angle represented by the inside faces of said first-named parts, of an angle brace formed to coincide with said angle and having its apex portion snugly fitting said recess and means for securing the angle brace to said parts, substantially as described.

2. In a table or the like, the combination, 10 with two parts arranged at an angle to each other and a third part arranged at the adjoining ends of said parts, said third part having a vertical Y-shaped recess on the inside thereof, of an angle-brace formed to coincide with

said angle and having an exterior rib at the 15 apex of its angle and arranged in the angle formed by said first-named parts with its ribbed portion fitting the recess of the third part, and means for securing the angle brace to said parts, substantially as described. 20

In testimony, that I claim the foregoing, I have hereunto set my hand this 24th, day of January 1907.

EDWIN P. WANNER.
